BORING BAR

Edward A. Zempel, Milwaukee, Wis.

Application July 20, 1946, Serial No. 685,039

5 Claims. (Cl. 77—58)

1

This invention appertains to boring bars and more particularly to a novel cutter insert therefor.

One of the primary objects of this invention is to provide a boring bar having a novel cutter insert embodying a pair of floating cutter blocks carrying the cutter or blades with means for automatically centering the blocks relative to the insert and the bar.

Another salient object of the invention is to provide means for adjusting the floating blocks for size or wear from either side of the insert without removing the insert from the bar, the centering device automatically locking and holding the blocks in correct position relative to each other and the bar.

A further object of this invention is to provide a micrometer adjustment for the floating blocks, whereby the blocks can be accurately and conveniently set to the exact desired size.

A further important object of my invention is to provide novel means for associating the floating blocks with a center supporting block, whereby the floating cutter blocks will be adequately supported from the supporting block.

A still further object of the invention is to provide means for removably associating cutter blades or tips with the floating cutter blocks, whereby new tips can be associated with the blocks when the original tips are worn down beyond a predetermined point.

A still further object of my invention is to provide novel means for associating the insert with the boring bar itself, whereby the boring bar will not be weakened and whereby the insert will be effectively supported by the bar.

With these and other objects in view the invention consists in the novel construction, arrangement and formation of parts, as will be hereinafter more specifically described, claimed and illustrated in the accompanying drawings, in which drawings

Figure 1 is a fragmentary longitudinal sectional view through a boring bar showing my novel insert connected therewith, the bar being ready for use.

Figure 2 is a diametric sectional view through the bar taken substantially on the line 2—2 of Figure 1 looking in the direction of the arrows.

Figure 3 is a fragmentary top plan view of the boring bar with my novel insert, parts of the view being shown broken away and in section.

Figure 4 is a fragmentary longitudinal center sectional view through the bar and insert, the section being taken substantially on the line 4—4 of Figure 3, the view showing, however, the floating blocks after adjustment from one side and prior to the centering thereof.

Figure 5 is a diametrical sectional view taken on the line 5—5 of Figure 4 looking in the direction of the arrows.

2

Figure 6 is a view similar to Figure 5 but showing the floating cutter blocks after the centering thereof.

Figure 7 is a diametrical sectional view through the boring bar and insert taken substantially on the line 7—7 of Figure 1 looking in the direction of the arrows.

Referring to the drawing in detail, wherein similar reference characters designate corresponding parts throughout the several views the letter B generally indicates the boring bar and I the insert therefor.

In accordance with this invention, the boring bar B adjacent to its front end is provided with a diametrically extending slot 10. The insert I is of an exact size to fit snugly within the slot, as will be apparent from the drawings.

The insert I includes a center guide and supporting block 11 and a pair of floating cutter blocks 12 and 13. These blocks 12 and 13 are of identical shape and their inner edges are provided with notches 13' in which is fitted the supporting guide block 11. The forward ends of the blocks 12 and 13 receive the cutting blades or tips 14 and 15 and these tips can be formed from high speed tool steel or tungsten carbide. The inner ends of the tips or cutters carry shanks 16 which are received in sockets 17 formed in the floating blocks. The inner ends of these blocks 12 and 13 can be provided with knockout openings 18 communicating with the sockets, so that a suitable tool can be inserted in the sockets for forcing out the tips. If desired set screws can be threaded into the floating blocks against the shanks to insure against the accidental displacement of the cutters or tips from the blocks.

Attention is called to the fact that a part of the tip rests against the forward wall of the boring bar.

40 The floating blocks are adapted to be guided and adjusted on the center guide and supporting block 11 and consequently this guide and supporting block 11 adjacent to its forward end is provided with a guide opening 19 which extends centrally through the block. This opening receives guide pins 20 and the pins 20 are held against movement by set screws 21 which are threaded into openings 22 in the floating blocks 12 and 13. The openings 22 align with the opening 19 in the center guide and supporting block and the pins also extend into the openings 22.

In rear of the opening 19, the center and supporting block 11 is provided with a similar opening 23 and this opening has fitted therein a guide sleeve 24. The guide sleeve 24 is internally threaded and these threads are of a certain definite pitch for a purpose which will be later set forth. The terminals of the sleeve 24 are slidably fitted in openings 25 formed in the floating blocks and outer ends of these openings are counter-bored to provide stop shoulders 26. Adjust-

ing screws 27 and 28 are threaded into the opposite ends of the sleeve 24 and the heads of the screws are adapted to abut against the shoulders 26. A tool opening is provided in the head of each screw to facilitate the turning thereof and the outer surface of the floating blocks 12 and 13 around the heads of the screws can be calibrated as at 29. The heads of the screws themselves can be provided with an indicating pointer 30 for cooperation with the markings.

From the description so far, it can be seen that the floating blocks are slidably mounted both on the pins 20 and on the guide sleeve 24. Thus twisting movement of the floating blocks relative to the center and supporting block 11 is prevented.

The floating blocks on one side and adjacent to their forward ends are provided with beveled or inclined surfaces 31. Threaded diametrically into the boring bar B is an adjusting and centering screw 32. The inner end of this screw is tapered as at 33 and the taper on the screw matches the bevel surface 31 on the floating blocks 12 and 13.

When it is desired to adjust the floating blocks 12 and 13 and the cutter or tips 14 and 15, say to a larger size one of the screws 27 or 28 is turned in the desired direction to feed the same outwardly and the number of turns of the selected screw or partial turn is carefully computed and each turn of a screw moves the same an exact distance known to the operator. Prior to the adjustment of the screws 27 or 28 the centering screw 32 is threaded outwardly a desired distance, see Fig. 5, this allows movement of the cutter blocks. After the selected screw has been adjusted, the centering screw is then turned tight into the boring bar and its tapered leading end 33 will engage against the beveled surfaces of the cutter blocks and automatically center the cutter blocks in the boring bar.

It is to be also understood that the centering screw 32 can be turned out as shown in Figure 5 to release cutter blocks, so that the same can float in the bar for reaming or finishing.

The bar itself is not weakened in any way and the slot is reinforced by the fact that the insert occupies the slot and it is to be also noted that the slot extends through the dead center of the bar.

It is to be also noted that the adjustment and guide for the floating blocks is back of the cutting edge of the tips 14 and 15 and this feature insures the proper taking up of the cutting strains.

Changes in details may be made without departing from the spirit or scope of my invention but what I claim as new is:

1. A boring tool comprising a bar having a diametrically extending slot therein adjacent to its forward end, a removable insert snugly fitted in said slot including a center guide block, a pair of like companion normally floating cutter blocks slidable on the center supporting block, cutter tips carried by the floating cutter blocks, guide pins between the center supporting block and the floating cutter blocks, a guide sleeve disposed in rear of said guide pins and extending through the center supporting block and the floating cutter blocks, said sleeve having its opposite terminals internally threaded, and headed screws threaded into the opposite ends of the sleeve, the heads of these screws being adapted to bear against the floating cutter blocks.

2. A boring tool comprising a bar having a di-

ametrically extending slot therein adjacent to its forward end, a removable insert snugly fitted in said slot including a center guide block, a pair of like companion normally floating cutter blocks 5 slidable on the center supporting block, cutter tips carried by the floating cutter blocks, guide pins between the center supporting block and the floating cutter blocks, a guide sleeve disposed in rear of said guide pins and extending through 10 the center supporting block and the floating cutter blocks, said sleeve having its opposite terminals internally threaded, and headed screws threaded into the opposite ends of the sleeve, the heads of these screws being adapted to bear against the floating cutter blocks, said cutter tips 15 being disposed forwardly of the guide means and the sleeve and adjusting screws.

3. A boring tool comprising a bar having a di- 20 ametrically extending slot therein adjacent to its forward end, a removable insert snugly fitted in said slot including a center guide block, a pair of like companion normally floating cutter blocks 25 slidable on the center supporting block, cutter tips carried by the floating cutter blocks, guide pins between the center supporting block and the floating cutter blocks, a guide sleeve disposed in rear of said guide pins and extending through the center supporting block and the floating cutter blocks, said sleeve having its opposite terminals 30 internally threaded, and headed screws threaded into the opposite ends of the sleeve, the heads of these screws being adapted to bear against the floating cutter blocks, said floating cutter blocks being calibrated around the heads of the screws 35 and said heads being provided with indicating points for cooperation with said calibrations.

4. A boring tool comprising a bar having a di- 40 ametrically extending slot therein adjacent to its forward end, a removable insert snugly fitted in 45 said slot including a center guide block, a pair of like companion normally floating cutter blocks slidable on the center supporting block, cutter tips carried by the floating cutter blocks, guide pins between the center supporting block and the floating cutter blocks, said sleeve having its opposite terminals internally threaded, and headed screws 50 threaded into the opposite ends of the sleeve, the heads of these screws being adapted to bear against the floating cutter blocks, and means carried by the bar for centering and locking the floating cutter blocks in said bar.

5. An insert for boring bars comprising a center supporting block, a pair of normally floating companion cutter blocks slidably mounted on the center supporting block, cutter tips removably carried by the forward ends of the cutter blocks, 60 guide means for said cutter blocks carried by the forward end of the center supporting block, and means carried by the rear end of the center supporting block for limiting the sliding movement of the cutter blocks thereon.
